UNITED STATES PATENT OFFICE

JESSE G. KING, OF DAYTON, OHIO, ASSIGNOR, BY MESNE ASSIGNMENTS, TO FRIGIDAIRE CORPORATION, A CORPORATION OF DELAWARE.

REFRIGERATING APPARATUS

Application filed November 20, 1926. Serial No. 149,745.

This invention relates to cooling units for mechanical refrigerating apparatus and particularly to cooling units which are adapted to be installed in refrigerator cabinets of the household type.

It is one of the objects of the invention to provide a cooling unit of simple and economical construction having provisions for freezing or congealing substances very quickly and also adapted to maintain the food compartment of the cabinet at the desired low temperature.

My invention contemplates providing a cooling unit having, what may be termed, a freezing zone for quickly cooling or congealing a substance, and having, what may be termed a cooling zone, which is adapted to insure the general refrigeration of the cabinet. In carrying out my invention I so construct and arrange the heat exchange means of the cooling unit, which may be formed of ducts or otherwise, that a portion thereof provides the freezing zone and another portion provides the cooling zone. I arrange the material providing the cooling zone so that it protects or shields at least three sides of the freezing zone from the warmer effect of the air or cooling medium which flows over the cooling unit in normal operation. My arrangement is such that although a relatively large protective cooling zone is provided for the freezing zone, the effective cooling action of the cooling zone portion is such that the refrigerator is maintained at the desired temperature, not too cold for general refrigeration, while at the same time the freezing zone functions to cool substances quickly.

It is another object of my invention to provide a cooling unit of the header and duct means type in which the duct means which provides the freezing zone is distinct from the duct means which provides the cooling zone so that one is not influenced by the other to further the maintaining of different temperatures of the zones.

Further objects and advantages of the present invention will be apparent from the following description, reference being had to the accompanying drawings, wherein a pre-

fferred form of embodiment of the present invention is clearly shown.

In the drawings:

Fig. 1 is a front elevation of the refrigerator cabinet with its doors open to show the cooling unit construction in accordance with the present invention. 55

Fig. 2 is a fragmentary, vertical, sectional view of refrigerator cabinet shown in Fig. 1 on an enlarged scale, this view showing the 60 cooling unit in front elevation.

Fig. 3 is a side elevation of the cooling unit.

Figs. 4 and 5 are sectional views on the lines 4—4 and 5—5 respectively of Fig. 2.

Referring to the drawings, 20 designates a 65 refrigerator cabinet which is divided by a horizontal partition 21 and a vertical partition 22 into a food compartment 23 and a cooling compartment 24. The wall 22 is provided with a flue 25 through which warm air 70 enters the cooling compartment 24, and the wall 21 is provided with a flue 26 through which cold air passes from the cooling compartment 24 to the food compartment 23. A baffle plate 27 supported by the wall 21 directs 75 moisture which drips from the cooling unit above, upon the upper surface of the wall 21 from which the moisture flows through a drain pipe 28.

The cooling unit comprises an elongated 80 header 30 which is supported within the cooling chamber 24 by brackets 31 and 32. Liquified refrigerant is conducted from refrigerating apparatus (not shown) through a pipe 33 and a fitting 34 to the header 30, and an 85 evaporated refrigerant is conducted from the header through pipes 35 and 36 to the liquifying apparatus of the refrigerating machine.

A plurality of ducts provided by 90 looped pipes 40 of metal of good thermal conductivity form a freezing or loop section, the primary purpose of which is to provide a freezing zone. The loops of the section are each connected with the header 30 and cooperate therewith to enclose a freezing space 95 41 which is isolated from air which circulates through the chamber 24. The space 41 is adapted to receive one or more shelves or sleeves 42 of metal of good conductivity. 100 These sleeves are attached to and thermally

- connected to the ducts 40, and each is adapted to receive a metal tray 43 for containing matter to be frozen. As stated before, the walls of the header 30 and of the ducts 40 co-operate to impede circulation of air through the space 41 so that this space becomes much colder than other parts of chamber 24. The frost which collects upon the ducts 40 assists in isolating the space 41.
- 10 In order to cool the air which circulates through the cooling chamber 24 the header 30 is connected with a plurality of looped pipes 45 of metal of good thermal conductivity, these pipes being spaced more remote 15 from the freezing chamber than the pipes 40 and forming an air cooling section, the primary purpose of which is to cool the circulating air. In order to increase the circulation of refrigerant through the pipes 40 relative to the circulation of the refrigerant 20 through the pipes 45 the latter are provided with restrictions represented by the lines 46 in Figs. 4 and 5. These restrictions 46 are provided by smashing or squeezing together 25 the walls of pipes 45 as indicated at 47. These restrictions may be exceedingly narrow, if not zero width. Thus the yoke portions 48 of pipes 45 are isolated from the leg portions 49. Since the circulation of the refrigerant 30 in pipes 49 is impeded and the refrigerant may be circulated relatively free through the pipes 40, the rate of heat transfer through the pipes 40 will be greater than through the pipes 49. Hence the desired low temperature 35 of the freezing space 41 will be reached in less time than if the pipes 45 were not restricted.
- It is apparent that most, if not all, of the circulation of refrigerant in the pipes 45 will 40 take place in leg portions 49 above the restriction 47. The yoke portions 48 will therefore operate as fins or thermal conductors which are thermally connected with the refrigerant ducts 49. While the restricted flow 45 of refrigerant in the ducts which will circulate air could be provided by simply using ducts connected to the header and closed at their lower ends, the present invention is advantageous in that it obviates the necessity of soldering or hermetically closing the lower ends of such ducts. It is not necessary that 50 the passage 46 be hermetically closed. The walls 47 may be squeezed together sufficiently 55 to provide a very narrow restriction. Any refrigerant which seeps from the leg portions 49 through the restrictions 46 will be received in the yoke portions 48 wherein it will evaporate and return through the passages 46. If air cooling ducts closed at the lower ends were used and if the bottom enclosure should become defective some of the refrigerant of course would leak out through the bottom of these ducts. This fault is 60 eliminated in the present invention since the

air cooling ducts 49 are provided by continuous loops of pipe.

By virtue of this construction it will be apparent that the cooling unit provides a relatively cold or freezing zone adapted for 70 freezing or congealing a substance and a cooling zone which lies outwardly of at least three sides of the freezing zone, in the path of the circulating air. The ducts 45 bound or provide the cooling zone, and it will be 75 seen that the legs 49 and yoke 48 are in intimate thermal association with the air which flows downwardly over the sides and under the cooling unit and that such air is cooled thereby to the desired temperature suitable 80 for general cooling within the refrigerator. The portions 40 being nested within the cooling zone enclosure, which extends throughout the length of the freezing zone, are protected by the cooling zone from the effects of 85 the relatively warm air circulating along the sides and below the cooling unit, and it may be said therefore, that the material of the cooling zone provides, without the aid of additional means, a shield of heat-exchange 90 material for shielding the freezing zone from the action of the circulating air. As previously stated, the material of the cooling zone protects three sides of the freezing zone. This necessitates, of course, a relatively large 95 cooling zone material surface. By means of the restrictions 46, I materially reduce the effective cooling action of cooling zone portion and in this manner the temperature of the storage compartments are maintained at the 100 desired temperature, not too cold for general refrigeration, while the freezing zone is maintained at a temperature for quickly 105 freezing substances. Preferably the more or less dormant refrigerant portion of the cooling zone is provided, as shown, at the lower portion of the cooling unit at which point, due to the cooling action imparted to the downwardly moving air, the differential of temperature between the freezing zone and cooling 110 zone is small, and the yoke portion 48 functioning somewhat like a fin will provide at this point sufficient protection for the freezing zone from the circulating air.

The legs 49 may be braced together by 115 metal strips 50 which are attached to the flattened portions 47 of pipes 45. If desired, the strip 50 may be made of metal of good heat conductivity and thermally bound to the legs 49 in order to provide heat absorbing 120 elements in addition to yoke portions 48.

While the form of embodiment of the present invention as herein disclosed, constitutes a preferred form, it is to be understood that 125 other forms might be adopted, all coming within the scope of the claims which follow.

What is claimed is as follows:

1. A cooling unit for mechanical refrigerators comprising, a header, a plurality of 130

ducts connected with the header and co-operating with the header to enclose a freezing space, and a plurality of ducts more remote from the freezing space and having a restriction for offering greater resistance to circulation of refrigerant than the ducts adjacent the freezing space.

2. A cooling unit for mechanical refrigerators comprising, a header, and pipe loops connected with the header, the walls of a loop being flattened at least at two places to obstruct the flow of refrigerant in an intermediate portion of the loop, the intermediate portion providing a fin thermally connected with the refrigerant ducts.

3. A cooling unit for mechanical refrigerators comprising, a header, a plurality of pipe loops connected with the header and co-operating therewith to enclose a freezing space, and a plurality of pipe loops connected with the header and surrounding the loops which enclose the freezing space, the second mentioned loops having restrictions for impeding circulation of refrigerant in said loops for the purpose specified.

4. A cooling unit according to claim 3, in which the second mentioned loops are provided with restrictions tending to isolate the yoke portions from the leg portions of these loops, the leg portions receiving refrigerant from the header and the yoke portions providing fins thermally connected with the leg portions.

5. A cooling unit for mechanical refrigerators adapted to be placed in the path of the circulating medium to be cooled thereby, said cooling unit comprising heat-exchange means in intimate contact with a refrigerant and with said medium to be cooled, said heat-exchange means having a portion including duct means constructed and arranged to provide a freezing zone, and another portion including duct means providing a cooling zone, said second-mentioned portion having a restriction for obstructing the flow of refrigerant therein, the material of the second-mentioned portion lying outwardly of the freezing zone in the path of the circulating medium and so constructed and arranged as to provide a shield of heat-exchange material for shielding the freezing zone from the action of the circulating medium.

6. A cooling unit for mechanical refrigerators adapted to be placed in the path of the circulating medium to be cooled thereby, said cooling unit comprising heat-exchange means in intimate contact with a refrigerant and with said medium to be cooled, said heat-exchange means having a portion including duct means constructed and arranged to provide a freezing zone, and another portion including duct means providing a cooling zone, means for obstructing the flow of refrigerant in the second-mentioned portion, the material of the second-mentioned portion ly-

ing outwardly of the freezing zone in the path of the circulating medium and so constructed and arranged as to provide a shield of heat-exchange material for shielding the freezing zone from the action of the circulating medium.

7. A cooling unit for mechanical refrigerators adapted to be placed in the path of the circulating medium to be cooled thereby, said cooling unit comprising a header, an inner refrigerant containing section including a set of loops connected with the header and providing a freezing zone adapted to receive an elongated ice tray, a second refrigerant containing section including a set of loops providing a cooling zone, said second set of loops being connected with the header in parallel circuit relation with the first set and lying outwardly of the freezing zone in the path of the circulating medium, said second-mentioned conduit means surrounding the freezing zone and constructed and arranged to shield the freezing zone, throughout the length thereof, from the action of the circulating medium.

8. A cooling unit for mechanical refrigerators adapted to be placed in the path of the medium to be cooled thereby, said cooling unit comprising a header, an inner duct loop refrigerant containing section connected with the header and providing primarily a freezing zone adapted to receive an elongated ice tray, and another refrigerant containing section connected in parallel circuit relation with the first section and formed to provide primarily a cooling zone, the material of said second section lying outwardly of the freezing zone in the path of the circulating means and so constructed and arranged as to provide, without the aid of additional means, a shield of heat-exchange material for shielding the freezing zone from the action of the circulating medium.

9. A cooling unit for mechanical refrigerators adapted to be placed in the path of the medium to be cooled thereby, said cooling unit comprising heat-exchange means in intimate contact with a refrigerant and with said medium to be cooled, said heat-exchange means having an inner refrigerant containing section constructed and arranged to provide primarily a freezing zone adapted to receive an elongated ice tray, and another refrigerant containing section providing primarily a cooling zone, the material of the second-mentioned section lying outwardly of at least three sides of the freezing zone in the path of the medium and so constructed and arranged as to provide, without the aid of additional means, a shield of heat-exchange material for shielding at least three sides of the freezing zone from the action of the circulating medium.

10. A cooling unit for mechanical refrigerators adapted to be placed in the path of the

circulating medium to be cooled thereby, said cooling unit comprising a header, an inner refrigerant containing section including a set of loops connected with the header and providing primarily a freezing zone adapted to receive an elongated ice tray, a second refrigerant containing section including a set of loops providing primarily a cooling zone, said second set of loops being connected with the header in parallel circuit relation with the first set and lying outwardly of the freezing zone in the path of the circulating medium, said second-mentioned conduit means being constructed and arranged to shield the freezing zone throughout the length thereof, from the action of the circulating medium.

In testimony whereof I hereto affix my signature.

JESSE G. KING.
